NAIL POLISH REMOVER DEVICE

Earl A. Erickson, Detroit, Mich.

Application July 9, 1956, Serial No. 42,172

Term of patent 14 years

(Cl. D86—10)

Fig. 1.

Fig. 2.

Fig. 3.

Fig. 1 is a perspective view of the nail polish remover device showing my new design;

Fig. 2 is a top plan of the same; and

Fig. 3 is a plan of the underside of the same.

I claim:

The ornamental design for a nail polish remover device, as shown.
